CARRYING CASE

Filed Aug. 9, 1929

UNITED STATES PATENT OFFICE

JAMES A. NOBLE, OF ROCHESTER, NEW YORK, ASSIGNOR TO EASTMAN KODAK COMPANY, OF ROCHESTER, NEW YORK, A CORPORATION OF NEW YORK

CARRYING CASE

Application filed August 9, 1929. Serial No. 384,531.

This invention relates to photography, and more particularly to camera carrying cases. One object of my invention is to provide an inexpensive, easily made, camera carrying case. Another object of my invention is to provide a camera carrying case in which the main part of the case is formed from a single blank of material and the edge walls are held together by means of a pair of cooperating plates. Another object of my invention is to provide an assembling means by which the edge walls of a camera carrying case can be fastened securely together. Another object of my invention is to provide a fastening means which does not require special tools. Another object of my invention is to provide a pair of cooperating plates, one having sockets and the other having spurs attached to the sockets for holding the facing edges of the camera walls together. Another object of my invention is to provide a fastening means for the facing edges of the side walls which is neat in appearance and which is not provided with any stitching or other fastening means extending through to the outside of the carrying case.

Coming now to the drawings wherein like reference characters denote like parts throughout;

Figure 1 is a perspective view of a camera carrying case constructed in accordance with and embodying a preferred form of my invention;

Figure 2 is a perspective view of one of the cooperating plates which go to fasten together the facing edges of the side walls of the camera;

Figure 3 is a perspective view of the other of the two cooperating plates which are used to fasten together with the side walls of the camera carrying case;

Figure 4 is a top plan view of a blank cut out to form the walls of a camera carrying case such as shown in Figure 1 and

Figure 5 is an enlarged detail section through one of the side walls of a carrying case constructed in accordance with, and embodying a preferred form of my invention.

Referring particularly to Figure 1, a camera carrying case may comprise a front

wall 1, a back wall 2, a bottom wall 3, and side walls designated broadly as 4.

Each of the side walls is composed of a series of layers of material which will be hereinafter more fully described. Referring to Figure 4, the blank from which the carrying case may be made is shown unfolded.

As will appear from this figure, the side walls may consist of two half sections 5-5. When the blank is folded up these sections face each other. They may be either in actual contact with each other along the edges 6, or these edges may be spaced somewhat from each other. The bottom wall 3 is formed of a series of sections 7 which are folded along the creased lines 8, and a series of flaps 9, fold together with their edges 10 either close to or touching each other. This blank is preferably made of cardboard, newsboard or like material.

To form a top or cover 11, for the carrying case, there is an extended flap which is provided with a series of weakened lines 12 separating areas 13 so that these are free to fold when the cover is turned about the upper edges of the camera carrying case.

In order to hold the facing edges 6 of the flap sides together, and in order to hold the flaps 9, which extend out from the stripe 7, which form the bottom wall of the camera carrying case together, I use a pair of cooperating plates shown in detail in Figures 1 and 2.

These plates are of similar shape, but are otherwise different. In Figure 2 the plate 14 is shown, this plate being preferably made from one or more laminations of cardboard or other relatively stiff material.

In the upper portion of plate 14 there is an opening or aperture 15 which is preferably not cut through the entire thickness of the material, but which is cut down into it to form a seat or pocket. This pocket is indicated at 16 in Figure 5. At the opposite end of member 14 there is a slot or opening 17 which may extend entirely through the material of which the plate 14 is made.

The second cooperating plate 18 is shown in Figure 3. This plate is preferably formed of a pair of laminations of material. I pref-

erably use an inner member 19 of a thin sheet of metal and an outer member 20 of cardboard or like material.

From the inner part 19 a pair of spurs 21 and 22 are stuck out. Spur 21 is preferably stuck out in a horizontal position and spur 22 is bent out as shown in Figure 3 so that a large part of the length of the spur will lie parallel to but spaced from the face of strip 18.

With the spur in this position the upper spur 22 is inserted into the pocket 15 of the cooperating plate 14 and then the spur 21 is entered through the slot 17 of plate 14 so that this last mentioned spur passes entirely through the plate and can be bent over flat against the inside of plate 14.

Before joining the plates in this manner, the flaps 5 and 9 are all folded so that they will lie between the two plates so that these plates serve as a clamp for holding these flaps together.

I prefer to place a decorative covering on each of these plates so that a smooth exterior will be presented by the side walls of the camera case.

This decorative covering may be in the form of a thin sheet of material such as leather, imitation leather or the like. In Figure 2 I have indicated the decorative covering for the cooperating plate 14 to consist of a blank of material 23 which has a series of flaps 24 extending around its periphery the size and shape of these parts being such that the flaps may be folded over and pasted against the inside face of the member 14.

Similarly the decorative covering for part 18 consists of a blank 25 having a series of flaps 26 which may be pasted over the edge of plate 18.

The edges of the blank after being pasted as above described may lie on the inner faces of the parts 14 and 18 as indicated in broken lines at 26'.

If desired, when putting the case together by uniting the edges of the side walls to the cooperating plates 14 and 18, a small amount of glue or other adhesive may be placed on the flap. This is diagrammatically illustrated in Figure 4 at 27. The flap will be held satisfactorily without the use of an adhesive, but this forms an additionally strong side wall to the case and since it is not necessary to take any great care to prevent the adhesive from smearing over the walls of the case, this can be readily done in assembling the case.

Among the advantages of a case constructed in accordance with my invention are the features that the inside of the case will be substantially smooth, free from stitching and the only part which will project at all on the inside of the case will be the end of spur 21. Since this spur is pressed down firmly after passing through slot 17,

it is generally pressed into the relatively soft wall of the cooperating plate 14 so that this spur will not scratch or otherwise mar the surface of a camera being placed in case.

The construction of the cooperating plates 14 and 18 not only provides a clamp by which the sides of the case may be firmly held together, but in addition, the construction particularly lends itself to the provision of a smooth, protective covering which is not marred by stitching. As indicated in Figure 1, the side walls 4 are perfectly smooth outside and if desired, the plate 18 may consist of a metallic inside plate 19 and a soft cardboard outside plate 20 so that the shape of plate 20 can be controlled by embossing, or the edges may be slightly rounded if necessary to give the desired effect.

Having thus described my invention, what I claim as new and desire to secure by Letters Patent is:

1. In a camera carrying case, the combination with a blank folded to form front, back, bottom, top and side walls, said side walls having facing edges and means for holding the facing edges together, including a pair of cooperating plates, one on each side of the cooperating edge walls, and metallic fastening means for joining the two plates together.

2. In a camera carrying case the combination with a blank folded to form front, back, bottom, top and side walls, said side walls having facing edges and means for holding the facing edges together, including a pair of cooperating plates, one on each side of the cooperating edges of the walls, and means for holding the plates together, including prongs carried by one plate and engaging the other plate.

3. In a camera carrying case the combination with a blank folded to form front, back, bottom, top and side walls, said side walls having facing edges, and means for holding the facing edges together, including a pair of cooperating plates, one on each side of the cooperating edge walls and prongs carried by one of the cooperating plates, said prongs entering into and being folded upon the other cooperating plate.

4. In a camera carrying case the combination with a blank folded to form front, back, bottom, top and side walls, said side walls having facing edges, and means for holding the facing edges together, including a pair of cooperating plates, one on each side of the cooperating edge walls, one plate having prongs extending therefrom and the other plate having openings to receive the prongs whereby one plate may be held toward the other by means of the prongs entering the opening and being folded against the plate.

5. In a camera carrying case, the combination with a blank folded to form front, back, bottom, top and side walls, said side walls

having facing edges and means for holding the facing edges together, including a pair of cooperating plates, one on each side of the cooperating edge walls, one plate having a plurality of apertures therein, a plurality of prongs on the other plate spaced in accordance with the apertures, said prongs of one plate being forced down to lie flat against the other plate after passing through the apertures therein whereby the side walls of the carrying case may be firmly clamped together.

6. In a camera carrying case, the combination with a blank folded to form front, back, bottom, top and side walls, said side walls having facing edges and means for holding the facing edges together, including a pair of cooperating plates, one on each side of the cooperating side walls, one plate having an 10 aperture and a pocket therein, and the other plate having a series of prongs spaced in accordance with the aperture and pocket of the other plate, said prongs being pressed flat against the plate whereby the edges of the 15 side walls may be firmly clamped between the two plates.

7. In a camera carrying case the combination with a blank folded to form front, back, bottom, top and side walls, there being flaps 20 on the side and bottom walls, adapted to extend toward each other and means for holding the flaps flat with their edges close together, comprising a pair of cooperative plates, an aperture and a pocket formed in 25 one of said plates and a pair of spurs extending from the other said plate, said spurs being adapted to enter the pocket and the aperture of the first-mentioned plate, both spurs to be folded flat against the plates to hold 30 the plates together, whereby said plate may form a clamp to hold the flaps flat and to hold the camera carrying case in shape.

Signed at Rochester, New York, this 6th day of Aug., 1929.

45 JAMES A. NOBLE.
